KARL EGGART, OF ARBON, SWITZERLAND, ASSIGNOR TO FIRMA ADOLPH SAURER, OF ARBON, SWITZERLAND.

SHUTTLE-OPERATING MECHANISM FOR EMBROIDERING-MACHINES.

1,200,177.

Specification of Letters Patent.

Patented Oct. 3, 1916.

Application filed August 1, 1914. Serial No. 854,447.

To all whom it may concern:

Be it known that I, KARL EGGART, a subject of the Emperor of Germany, residing in Arbon, Switzerland, have invented certain new and useful Improvements in Shuttle-Operating Mechanisms for Embroidering-Machines, of which the following is a specification, reference being had to the accompanying drawings, forming a part hereof.

This invention relates to means for operating or producing the required movement of the shuttles in shuttle embroidery machines and more especially in shuttle embroidery machines in which the operations of the embroidery mechanism are initiated or controlled by a jacquard mechanism or automat, and it has for its object the production of means whereby the throw of the shuttles can be lengthened or shortened through the action of devices intermediate the operating cams or other operating mechanism and the shuttle bars or transmitting lever system, without requiring the shifting of connections from one cam or set of cams to another cam or set of cams. The variation of the throw of the shuttles which is particularly contemplated in this case is that, for example, which is required in the changing from normal stitching to perforating and vice versa. In the embodiment of the invention illustrated in the drawings the action of the automat, under the control of the jacquard card, initiates or brings about the shifting or action of the intermediate devices referred to, whereby the effective length of the operating lever arm is lengthened or shortened for the purpose of lengthening or shortening the extent of movement of the shuttles.

The invention will be more fully explained hereinafter with reference to the accompanying drawings in which one embodiment thereof is illustrated and in which Figure 1 is a view partly in elevation and partly in sectional elevation, showing the improved mechanism and so much of a jacquard mechanism or automat and of an embroidery machine as is necessary to enable the invention to be understood. Fig. 2 is a top view of the parts shown in Fig. 1, the driving shaft, with its cams and its supports, being removed. Figs. 3, 4, 5 and 6 are detail views in elevation and on a some-

what larger scale than Figs. 1 and 2, showing the improved mechanism with parts in different positions. Fig. 7 is a detail view in section through the main operating lever. Fig. 8 is a detail view partly in section on the irregular plane indicated by the line A—B of Fig. 3. Fig. 9 is a detail view of the locking lever.

In the drawings the frame of an automatic embroidery machine of ordinary construction is indicated at 1 and at 2 is shown the usual driving shaft of the machine, the same being provided, in the construction shown, with two offset cams 3 and 4 which act respectively upon the two rollers 7 of the bell-crank or main operating lever 5, mounted at 6 on the frame of the machine. The bell-crank or main operating lever 5 operates or effects the required movement of the shuttle rails, one of which is shown at 8, through a link 9, a second bell-crank 10, and rods 11 (only one being shown) on which the shuttle bar 8 is mounted. The shuttle tracks 12 receive and guide the shuttles 13 in the usual manner.

In order that the throw of the shuttles may be varied, provision is made for varying the effective length of the nearly vertical or operating arm 14 of the bell-crank lever 5, the same being chambered longitudinally to receive a sliding bolt or head 15 which is provided with studs 18 to be engaged by the forked member of the link 9, the studs 18 moving in slots 19 in the lever arm 14. The sliding bolt, preferably cylindrical, is provided with two locking, annular grooves 16 and 17 adapted to be engaged by a locking bolt 21 so that the sliding bolt may be locked in one of its two operative positions, either in the position shown in Figs. 1, 3, 4 and 7, in which the effective length of the lever arm, that is, the radial distance of the studs 18 from the axis 6, is at its maximum, or in the position shown in Figs. 5 and 6, in which the studs 18 are at the inner ends of the slots 19 and their radial distance from the axis 6, and therefore the effective length of the lever arm, is the minimum. The locking bolt 21 is mounted in a guide 20 and is normally pressed forward, into locking position, by a spiral spring 22. A pin 23, carried by the head of the locking bolt, projects through slots in the wall of the guide 20 in front of the bolt operating arms 25, pivotally mounted on

the inner ends of the slots 19 and their radial distance from the axis 6, and therefore the effective length of the lever arm, is the minimum. The locking bolt 21 is mounted in a guide 20 and is normally pressed forward, into locking position, by a spiral spring 22. A pin 23, carried by the head of the locking bolt, projects through slots in the wall of the guide 20 in front of the bolt operating arms 25, pivotally mounted on

the main operating lever 5, one of such arms having connected thereto a spring 24 which normally withdraws the bolt operating arms, while the other carries a roller 26 which coöperates with the concentrically curved edge of the long arm 29 of a lever which is pivotally mounted at 27 on the lower and nearly horizontal arm of the main operating lever 5. The shorter arm 28 of this lever is provided with a roller 28' for a purpose to be described. The curved edge of the arm 29, which coöperates with the roller 26 of the bolt operating arm 25, is provided with two rounded notches 31 and 32. Movement of the lever arm 29 from either one of its alternative positions, such as that shown in Figs. 1, 3 and 4, or that shown in Figs. 5 and 6, acts upon the roller 26 to move it out of the corresponding notch 31 or 32, and therefore, through the arms 25, to withdraw the bolt 21 from the corresponding notch 16 or 17 of the sliding bolt 15, thereby permitting relative movement of the sliding bolt 15 and the arm of the bell-crank 5 in which it is mounted. Such relative movement takes place while the roller 26 is resting upon the curved edge of the arm 29 between the two notches 31 and 32 and as soon as one or the other of such notches registers with the roller 26, the spring 24 swings the arms 25 backward and the spring 22 throws the locking bolt forward into engagement with the locking groove 16 or 17, as the case may be, of the sliding bolt 15, thereby locking the sliding bolt 15 in one position or the other.

The roller 28' on the short arm 28 of the locking lever 28 29 enters a long slot 33 34 in a lever 35 which is pivoted at 37 on the support 36 and is pulled normally toward the axis 6 of the bell-crank lever 5 by a spring 35'. The two parts 33 and 34 of the slot 33 34 are offset as shown and are formed, at their adjacent ends, with stop shoulders 33' 34' respectively. When the lever 35 is in the position shown in Figs. 1, 3 and 6, the roller 28' may move in the portion or wing 33, but when the lever-arm 35 is in the position shown in Figs. 4 and 5, then the roller 28' is free to move only in the portion or wing 34 of the slot. It will be observed that the shifting of the lever 35 can take place only when the roller 28' is in its middle position with respect to the two ends 33' 34' of the slot 33 34, as indicated in Figs. 4, 5 and 6. Since the lever arm 35 is mounted on the support 36 and the locking lever 28 29 is mounted on the main operating lever or bell-crank 5, which is oscillated by the cams 3 and 4, it will be seen that the relative movement of the locking lever 28 29 and the main operating or bell-crank lever 5 is effected by the movement of the main operating lever 5 by the action of the cams 3 and 4, such relative movement taking place when

the roller 28' is resting against the shoulder 34', as shown in Fig. 4, or against the shoulder 33', as shown in Fig. 6.

The angular position of the lever arm 35 determines whether the shoulder 33' or the shoulder 34' shall be in position to hold the roller 28' against movement in one direction or the other and therefore whether the relative movement of the locking lever 28 29 with respect to the bell-crank lever 5 shall be in one direction or the other. The angular position of this controlling lever 35 is therefore placed under the control of the automat or jacquard mechanism. For this purpose the short shaft 37 on which the lever 35 is mounted is provided with a short arm 38 which carries a roller 39. The latter, under the influence of the spring 35', bears against the edge of a stop cam 40, the upper part 41 of which serves to hold the lever 35 in the position shown in Figs. 1, 3 and 6, while the low part 42 serves to permit the lever 35 to be swung by the spring 35' into the position shown in Figs. 4 and 5. The stop cam 40 is directly under the control of and is moved by the automat or jacquard mechanism through suitable devices, such as the link 43, the lever 45 mounted on the support 44, and the link 46 connected to a crank pin 47 on a shaft 49 of the jacquard mechanism 48, a pinion 50 splined on the shaft 49, being shifted by the needle mechanism 51 into or out of engagement with the rotating gear 52 of the jacquard mechanism. A half rotation of the shaft 49, from the position indicated in Fig. 1 causes the stop cam 40 to be moved from the position shown in Figs. 1 and 3 to the position shown in Fig. 4 and therefore permits the slotted controlling lever 35 to be moved by the spring 35' from the position shown in Figs. 1 and 3 into the position shown in Figs. 4 and 5. Another half rotation of the shaft 49 will cause the stop cam 40 to be moved from the position shown in Figs. 4 and 5 to the position shown in Figs. 1, 3 and 6, thereby moving the controlling lever 35 from the position shown in Figs. 4 and 5 to the position shown in Fig. 6.

The slotted bolt 15 is preferably moved with respect to the arm of the lever 5 in which it is mounted through a connection with the locking and shifting lever 28 29. As shown particularly in Fig. 8 a link 55 mounted at one end on a stud 56 which may project from the sliding bolt 15 through the slot on the corresponding side of the lever arm may have at its other end a stud 54 which enters a slot 53 in the lever-arm 29. The slot is slightly elongated, as shown, so as to permit a sufficient movement of the locking lever to withdraw the locking bolt 21 before the movement of the sliding bolt begins, the continued movement of the locking and shifting lever, after the locking bolt 130

has been withdrawn, producing a corresponding movement of the sliding bolt with relation to the bell-crank lever. This action is the same whether the sliding bolt is moved 5 in one direction or the other.

In describing the operation of the mechanism shown in the drawings let it be assumed that with the parts in the positions shown in Figs. 1 and 3, when the shuttles have their 10 full throw, the studs 18 being in the outer end of the slots 19, it is desired to shorten the throw of the shuttles. To accomplish this the point of connection between the corresponding arm of the bell-crank lever 5 must be shifted from the point shown in 15 Fig. 1 to a point nearer the axis of oscillation of the lever 5. It will be seen, upon examination of Fig. 3, for example, that the portions 33 and 34 of the slot 33 34 in the 20 lever 35 are curved substantially concentric with the axis 6 of the bell-crank lever 5, and it will be understood that with the parts in the relative positions shown in Fig. 3, as the bell-crank lever 5 is oscillated by the cams 25 3 and 4, the roller 28' reciprocates in the part 33 of the slot 33 34 and also that when the parts are in the positions shown in Fig. 5 the roller 28' reciprocates in the portion 34 of the slot 33 34. With the parts in the 30 positions shown in Fig. 3 and the roller 28' reciprocating in the portion 33 of the slot, at the moment when the roller is at or near the top of the part 33 of the slot, as shown in Fig. 6, the jacquard mechanism or automat 35 causes the stop cam 40 to be moved so as to permit the slotted controlling lever 35 to be moved from the position shown in Fig. 3 to the position shown in Fig. 4. At this instant the bell-crank lever 5 is at the extreme 40 of its oscillation toward the right, as also shown in Fig. 4, and then at once begins its oscillation toward the left. During the oscillation of the bell-crank lever toward the left the roller 28' rests upon the shoulder 45 34' and the consequence of the oscillation of the bell-crank lever toward the left is therefore, as shown in Fig. 5, to produce a relative movement of the locking lever 28 29 with respect to the bell-crank lever, from the 50 position shown in Fig. 4 to the position shown in Fig. 5. This movement, through the co-action of the curved edge of the lever arm 29 and the roller 26, withdraws the locking bolt 21 and releases the sliding bolt 15. 55 Through the provision of the slot 53 in the locking lever 28 29 the first effect of the relative movement of the locking lever is to cause the locking bolt 21 to be withdrawn, but as soon as that function is accomplished 60 the continued relative movement of the locking lever, which now becomes also a shifting lever, causes the sliding bolt 15 to be drawn from the position shown in Fig. 4 to the position shown in Fig. 5. As soon as this 65 relative position has been acquired, the notch

32 in the curved edge of the lever arm 29 permits the locking bolt 21 to move forward under the influence of the spring 22 and enter the locking groove 17 in the sliding bolt 15, which groove is then in line with the 70 locking bolt 21. The locking lever then continues to oscillate as before, but as the effective length of its working arm has been reduced the throw of the shuttles will be reduced correspondingly. 75

When the throw of the shuttles is to be increased from the short throw to the normal, long throw, the jacquard mechanism or automat, through another half rotation of the shaft 49, at the instant when the cams 80 3 are in positions shown in Fig. 5, causes a movement of the stop cam 40 from the position shown in Fig. 5 to the position shown in Fig. 6. The bell-crank lever 5 is then at the left hand limit of its oscillation. During the following oscillation to the right the roller 28' bears against the shoulder 33', as shown in Fig. 6, and the lever 28 29 remains relatively stationary. The bell-crank lever 5 therefore moves relatively to the locking 85 lever 28 29 and, as will now be clearly understood, the locking bolt 21 is withdrawn, held out of locking position and then permitted to move again into locking position. While it is so held out of locking position, 90 during the remainder of the forward or right hand oscillation of the bell-crank lever, the said bell-crank lever moves with respect to the sliding bolt 15 which, as already described, is connected by the link 55 and the locking and shifting lever 28 29 and the sliding bolt therefore reassumes, with relation to the bell-crank lever, the position shown in Fig. 7, in which relative position it is locked by the engagement of the locking bolt 21 95 with the locking groove 16 of the sliding bolt. Thereafter, therefore, the oscillations will be actuated by the bell-crank lever with a full, normal throw. 100

It will be understood that various changes 105 in details of construction and arrangement may be made to suit different conditions of use and that the invention, therefore, is not limited to the particular construction shown and described herein. 110

I claim as my invention:—

1. In an embroidering machine, the combination of a shuttle-bar, a main operating lever having an operating arm, operating connections between the operating lever and the shuttle-bar, mechanism for actuating the main operating lever, an automat, and means, the operation of which is initiated by the automat, for varying effective length 120 of the operating arm of the main operating lever.

2. In an embroidering machine, the combination of a shuttle-bar, a main operating lever having an operating arm, operating connections between the operating lever 125

and the shuttle-bar, mechanism for actuating the main operating lever, means actuated by said last named mechanism for shifting the point of connection between 5 said operating connections and the operating arm of the main operating lever, and independent pattern controlled devices for controlling the operation of said shifting means.

10 3. In an embroidering machine, the combination of a shuttle-bar, a main operating lever having an operating arm, operating connections between the operating lever and the shuttle-bar, mechanism for actuating the 15 main operating lever, means actuated by said last named mechanism for shifting the point of connection between said operating connections and the operating arm of the main operating lever, an automat, and 20 means, the operation of which is initiated by the automat, for controlling said shifting means.

4. In an embroidering machine, the combination of a shuttle-bar, a main operating 25 lever, operating connections between the operating lever and the shuttle-bar, said operating connections including a shiftable connection on the operating lever, mechanism for actuating the main operating 30 lever, means operated by said actuating mechanism for shifting said shiftable connection, and independent pattern controlled devices for controlling the operation of said shifting means.

35 5. In an embroidering machine, the combination of a shuttle-bar, a main operating lever, operating connections between the operating lever and the shuttle-bar, said operating connections including a shiftable 40 connection on the operating lever, mechanism for actuating the main operating lever, a shifting lever mounted on the main operating lever and connected to said shiftable connection, and means to control said 45 shifting lever.

6. In an embroidering machine, the combination of a shuttle-bar, a main operating lever, operating connections between the operating lever and the shuttle-bar, said operating 50 connections including a shiftable connection on the operating lever, mechanism for actuating the main operating lever, a locking device for said shiftable connection, a locking and shifting lever mounted 55 on the main operating lever, said shifting lever being operatively connected with said shiftable connection and in operative relation with said locking device, and means to control said shifting and locking lever.

60 7. In an embroidering machine, the combination of a shuttle-bar, a main operating lever, operating connections between the operating lever and the shuttle-bar, said operating 65 connections including a shiftable connection on the operating lever, mecha-

nism for actuating the main operating lever, a shifting lever mounted on the main operating lever and operatively connected to said shiftable connection, a controlling lever co-operating with said shifting lever, and 70 means to control said controlling lever.

8. In an embroidering machine, the combination of a shuttle-bar, a main operating lever, operating connections between the operating lever and the shuttle-bar, said 75 operating connections including a shiftable connection on the operating lever, mechanism for actuating the main operating lever, a shifting lever mounted on the main operating lever and operatively connected to 80 said shiftable connection, a controlling lever in operative relation with said shifting lever, an automat, and means actuated by the automat for controlling said controlling lever.

9. In an embroidering machine, the combination of a shuttle-bar, a main operating lever, operating connections between the operating lever and the shuttle-bar, said operating connections including a shiftable 90 connection on the operating lever, mechanism for actuating the main operating lever, a shifting lever mounted on the main operating lever and operatively connected to said shiftable connection, a spring pressed controlling lever in operative relation with said shifting lever, a stop cam in operative relation with said controlling lever, an automat, and operating connections from said automat to said stop cam.

10. In an embroidering machine, the combination of a shuttle-bar, a main operating lever having an operating arm, a sliding bolt mounted on the operating arm of said main operating lever, operating connections 105 between said sliding bolt and the shuttle-bar, a shifting lever mounted on the main operating lever and operatively connected to said sliding bolt, and means to control said shifting lever.

11. In an embroidering machine, the combination of a shuttle-bar, a main operating lever having an operating arm, a sliding bolt mounted on the operating arm of said main operating lever, operating connections 115 between said sliding bolt and the shuttle-bar, a locking device for said sliding bolt, a shifting and locking lever mounted on the main operating lever and operatively connected to said sliding bolt and in operative relation 120 with said locking device, and means to control said shifting and locking lever.

12. In an embroidering machine, the combination of a shuttle-bar, a main operating lever having an operating arm, a sliding 125 bolt mounted on the operating arm of said main operating lever, operating connections between said sliding bolt and the shuttle-bar, a spring pressed locking bolt adapted to engage said sliding bolt, a shifting and 130

locking lever mounted on the main operating lever and operatively connected to said sliding bolt, and having a concentrically curved and notched edge for coöperation with the locking bolt, and means to control said shifting and locking lever.

13. In an embroidering machine, the combination of a shuttle-bar, a main operating lever having an operating arm, a sliding bolt mounted on the operating arm of said main operating lever, operating connections between said sliding bolt and the shuttle-bar, a locking device for said sliding bolt,

a shifting and locking lever mounted on the main operating lever in operative relation with said locking device and having a concentric slot, a link connection between said sliding bolt and said shifting and locking lever in said concentric slot, and means to control said shifting and locking lever.

This specification signed and witnessed this 20 day of July, A. D. 1914.
